[57] CLAIM

The ornamental design for a bottle, as shown and described.

DESCRIPTION

FIG. 1 is a side elevation of a bottle showing our new design;

FIG. 2 is a side elevation of the bottle rotated 45° from the FIG. 1 position;

FIG. 3 is a top plan view thereof;

FIG. 4 is a bottom plan view thereof;

FIG. 5 is a side elevation of the bottle rotated to show the two indented panels not shown in FIGS. 1 and 2; and

FIG. 6 is a sectional view taken along the line 6—6 in FIG. 2.

FIG. 1

FIG. 2

FIG. 3

FIG. 4

FIG. 5.

FIG. 6.
